UNITED STATES PATENT OFFICE.

JACOB WARSHAWSKY, OF NEW YORK, N. Y., ASSIGNOR OF ONE-HALF TO ABRAHAM RODAK, OF NEW YORK, N. Y.

RAIN-SHIELD.

1,391,925.

Specification of Letters Patent. Patented Sept. 27, 1921.

Application filed January 26, 1920. Serial No. 354,084.

To all whom it may concern:

Be it known that I, JACOB WARSHAWSKY, a citizen of the United States, residing in the Bronx, in the city and State of New York, have invented certain new and useful Improvements in Rain-Shields, of which the following is a specification.

The invention relates to a temporary protection from the weather and more particularly to such a temporary covering for the shoulders and for the head of a person with the hat worn thereon.

The accompanying drawings, referred to herein and constituting a part hereof, illustrate one embodiment of the invention, and together with the description, serve to explain the principles of the invention.

Of the drawings:

Figures 1 and 2 show the article as worn 20 on the person as a protection against the storm;

Fig. 3 is a side view of the article;

Fig. 4 is a development of the sheet from which the article is made; and

Fig. 5 shows the application of the reinforcing strip and the tying means.

Objects of the invention are to provide a temporary protection for hats and clothing, and for the wearers thereof, from rain, sleet, 30 snow and other meteorological inclemencies, such as might be generally and economically available at news-stands, drug stores, cigar stores and other handy places on occasions when umbrellas have not been prepared beforehand or have been forgotten.

The common or usual procedure is to "rent" umbrellas, that is, the traveler deposits the purchase price or supposed value of the umbrella with the dealer and upon 40 subsequently returning the umbrella, the money is refunded, less the rental charge, which is usually ten cents per day. This necessitates the return of the umbrella upon the next succeeding day, frequently at great 45 inconvenience, or as an alternative, the multiplication of the rental charge if not so returned.

The present invention provides a protector from the weather which is purchased outright, usually at the same expense as renting an umbrella, which protector is discarded as soon as his ultimate destination is reached by the traveler. The article of the present invention also is neat and compact

for packaging and handling prior to sale and use.

Referring to the illustrative embodiment of the accompanying drawings, in Figs. 1 and 2 the protector is shown worn over the hat and the coat about the shoulders. The material of which the protector is made must possess the property of completely shedding rain, snow or sleet for a fairly protracted time. It must be also of sufficiently low cost to permit of its temporary use, that is, to permit of its being worn once through a storm and then thrown away. It also should be, preferably, capable of being folded flatly and compactly without impairing its weather-shedding properties, so that it can be compactly and attractively packaged for sale. It is also essential or desirable that it be of reasonably neat and attractive appearance, so that an ordinary traveler would wear it without hesitation. It is also desirable that the material be attractively and unobtrusively colored or colorable.

I have found waterproofed paper, such as oiled or paraffined paper, to meet these requirements. The device is also rendered 80 sufficiently strong to withstand ordinary use, and for this purpose, a reinforcing strip 1 is run about the edges thereof and suitably attached thereto as by stitching 9, and the fastening means, such as strings 2 and 3, are 85 fastened to the reinforcing strips 1.

The device is formed preferably of a single sheet 4, which is shaped substantially as shown in Fig. 4, the edges 5 and 6 being brought together and permanently united by 90 sewing, cementing, or otherwise fastening as desired.

The device after edges 5 and 6 are fastened together, may be folded flat as shown in Fig. 3, and may be folded transversely again 95 one or more times for packaging. The part 7 incloses the head and head gear of the wearer and the part 8 incloses his shoulders. The manner of wearing will appear from Figs. 1 and 2.

It will be understood that departures may be made from the details of the invention as herein embodied and described within the scope of the appended claims without departing from the principles of the invention 105 and without sacrificing its chief advantages.

What I claim is:—

1. A temporary and inexpensive protector

from the weather, adapted to fit loosely over the head and shoulders, consisting of a single sheet of waterproofed paper, cut approximately in the form of a thick and inverted letter **T**, the stem portion forming the head protecting portion, the free end edge of the stem of the **T** being folded upon itself and stuck together to form the top of the protector, and the cross-bar of the **T** folding about the shoulders of the wearer and means for fastening the ends of the cross-bar part under the chin of the wearer.

10 2. A temporary and inexpensive protector

for the head and shoulders from the weather consisting of a single sheet of waterproofed paper shaped to conform to the head and shoulders when worn and to fold flatly for preliminary packaging and sale, and having reinforcement of strong material attached thereto and extending entirely about the exterior edge and strings attached to the binding material to fasten it beneath the chin by a single knot.

15 In testimony whereof I have signed my name to this specification.

20 JACOB WARSHAWSKY.
